(No Model.)

J. C. BROMLEY.

STEAM ACTUATED VALVE.

No. 398,491.

Patented Feb. 26, 1889.

UNITED STATES PATENT OFFICE.

JOHN C. BROMLEY, OF ROCK ISLAND, ILLINOIS.

STEAM-ACTUATED VALVE.

SPECIFICATION forming part of Letters Patent No. 398,491, dated February 26, 1889.

Application filed May 4, 1888. Serial No. 272,804. (No model.)

To all whom it may concern:

Be it known that I, JOHN C. BROMLEY, of Rock Island, in the county of Rock Island and State of Illinois, have invented certain new and useful Improvements in Steam-Actuated Valves; and I do hereby declare that the following is a full, clear, and exact description thereof, reference being had to the accompanying drawings, and to the letters of reference marked thereon, which form part of this specification, in which—

Figure 1 is a vertical longitudinal section through a steam-cylinder and valve-chest, illustrating my invention. Fig. 2 is a detail 15 top plan view of the steam-cylinder, the valve-chest being removed. Fig. 3 is a cross-sectional view of line xx , Fig. 1.

This invention is an improvement in steam-engines, its object being to provide an automatic steam-actuated valve for controlling the ingress and egress of steam to and from the cylinder; and it consists in the novel construction of the valve and piston-head, and in the arrangement of the port-passages, as 25 hereinafter described, illustrated in the drawings, and clearly specified in the claims hereto appended.

Referring to the drawings by letter, A represents the cylinder, the upper surface, a , of 30 which is dressed to form a seat for and steam-tight joint with the base of a cylindrical valve-chest, B.

C is a steam-ingress port formed centrally in part a of cylinder A and opening into 35 chest B at c , as shown.

D E are the main steam-ports extending through part a of the cylinder to the opposite ends thereof and opening into chest B at d e on opposite sides of openings c , as shown.

F is a small port-channel communicating 40 with the interior of cylinder A near the port E. The main part of the channel is formed by grooving the part a , as shown, the groove being closed by the base of the valve-chest 45 when the latter is bolted in place. Channel F extends to and communicates with the valve-chest at the end approximating port D.

G is a port-channel corresponding to channel F, but extending from the end of cylinder 50 A approximating port D to the end of the valve-chest approximating port E.

H designates the piston-head, formed of the plates h h and interposed packing. I I are annular grooves in the peripheries of plates h , which communicate with the interior of the cylinder by perforations i i , as shown. The thickness of the head H is such that when at opposite extremes of its movement in cylinder A the groove I nearest the center of the cylinder is in communication with one of the 55 channels, F or G.

J designates the valve, preferably cylindrical, and having a central reduced portion, j , at opposite ends of which are two collars, K k , which have annular packed grooves, as 60 shown.

L l are heads on the ends of the valve, which is reduced between said heads and the collars, as shown at P p . These heads are properly packed to prevent leakage of steam, and have 70 annular grooves M m , respectively, and a series of perforations, N n , respectively, extending through the face of the valve and communicating with the grooves, as shown.

O o are exhaust-ports leading from chest B, 75 near the opposite ends thereof. Grooves M m are adapted to communicate with port-channels F G and ports O o , respectively, when the valve is in proper position, as hereinafter explained. The ports C O o are connected with any proper delivery and exhaust pipes.

The operation of the engine is as follows: Valve J being in the position shown in the drawings, so that port C communicates with 85 port E through the annular channel between the collars K k , and port D communicates with port o through the annular chamber in the chest between collars k and head l of the valve, steam entering port C passes through 90 port E to the cylinder, forcing piston-head H to the opposite end of the cylinder, as shown, and as head H arrives at this position its groove I communicates with channel G, the steam under pressure in the cylinder enters 95 groove I by openings i , and from said groove passes into channel G, passing through the latter to groove M in valve-head L, and, escaping from groove M by openings N, impinges against the head of valve-seat B and 100 forces the valve back until its head l strikes the opposite side of the chest. This move-

ment of the valve shifts collars K *k*, causing them to establish communication between ports C and D and ports E and O, so that the ingress and egress passages of the steam are automatically and instantaneously transposed. The head H is then forced to the opposite end of the cylinder, and the steam passes into channel F, to groove *m*, into the valve-chest, driving the valve back to its former position. When the valve is in the position shown, the groove *m* communicates with port *o*, as does also the port D, owing to the width of the opening of port *o*; but this communication of grooves *m* or M with ports *o* or O (according to the position of the valve) is not effected until the valve is properly shifted, and ere this communication is established the mouths of the channels F or G are closed by the face of heads L or *l*, as evident. By this means the steam is exhausted from the valve-chest, and the valve will not be hindered in its movements by steam-pressure in the wrong end of the chest. The valve, when shifted, establishes communication between the grooves *m* and channel F, or groove M and channel G, before it has completed its stroke, and the steam passing through said channel and grooves exerts a momentary back-pressure between the head of the valve and the end of the chest sufficient to cushion the latter and prevent injurious and annoying "knocking" of the valve in the chest.

Q is a short pitman-rod playing through a proper stuffing-box in one end of chest B. This rod is pivotally connected to a rocking lever, R, pivoted upon an arm, S, projecting from the base of chest B, as shown. By means of these devices the valve can be thrown into working position should it accidentally jar out of position.

Having described my invention, I claim—

1. The combination of the cylinder and valve-chest, the ports D E, and channels F G,

communicating with the opposite ends of said cylinder and centrally with the chest, and the ingress-port C, communicating with the center of the valve-chest, and exhaust-ports O *o*, communicating with the ends of said chest, with the piston and the steam-actuated valve in said chest adapted to simultaneously establish communication between the port C and one port, E or D, and to establish communication between the remaining one of said ports and one exhaust-port, O or *o*, all constructed and arranged to operate substantially in the manner and for the purpose described.

2. The combination of the cylinder and valve-chest and the steam ingress and egress ports and channels therein, constructed and arranged substantially as described, with the piston-head H, having annular non-communicating grooves I and perforations *i i* in its opposite faces communicating with said grooves and the valve in said chest, all constructed and arranged to operate substantially as and for the purpose described.

3. The combination of cylinder A, its ports D and E, channels F and G, and piston-head H, grooved and perforated substantially as described, and the valve-chest B, its ingress and egress ports C and O *o*, with the valve J, having collars K *k*, heads L *l*, and intermediate reduced portions, *j*, P, and *p*, and the annular grooves and perforations in heads L *l*, and the rods Q, lever R, and arm S, all constructed and arranged substantially in the manner and for the purpose described.

In testimony that I claim the foregoing as my own I affix my signature in presence of two witnesses.

JOHN C. BROMLEY.

Witnesses:

WILLIAM ADAMSON,
JAMES H. SOUTHWELL.
